UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

SPARK-GAP STRUCTURE.

Application filed October 2, 1922. Serial No. 591,798.

To all whom it may concern:

Be it known that I, JOSEPH SLEPIAN, a citizen of the United States, and a resident of Swissvale, in the county of Allegheny 5 and State of Pennsylvania, have invented a new and useful Improvement in Spark-Gap Structures, of which the following is a specification.

This invention relates to spark gaps, 10 more particularly to spark gaps which break down at voltages of 350 to 500 volts.

In practising my invention, I provide a pair of plane or flat plates or disks of high-resistance material and place between the 15 same a thin spacer or washer of suitable insulating material, such as mica, 3 to 5 mils in thickness.

It is well known that such insulating spacers placed between conducting electrodes 20 will break down over their edges at 350 to 450 volts. This is probably due to the high dielectric constant of the mica and the leakage over the short 5-mil edge.

When metallic or low-resistance plates 25 are used, the breakdown which occurs at the edge of the mica is followed by a discharge concentrated at that point. This discharge causes the mica to be charred, or otherwise disintegrated, and may cause the 30 metal to fuse together at that point. For this reason, such a gap using low-resistance or metallic plates has not proven satisfactory.

By using plates of high specific resistance, the discharge which starts next to the mica surface is limited in intensity by the resistivity of the material so that the energy 35 of the discharge is not all turned loose next to the mica but is distributed over the whole 40 face of the plate, and the discharge takes and maintains the form of a glow discharge. Thus, the mica edge is not affected by the discharge and such a gap 45 may be used over and over again without any deterioration.

This gap is particularly useful in application to the so-called disk-pile lightning arrester, such as I have described in my 50 copending applications, Serial No. 535,810, filed Feb. 11, 1922, for lightning arresters and Serial No. 536,910, filed Feb. 16, 1922, for disk structure.

The outstanding characteristic of lightning arresters of the type specified is that 55 the gaps individually break down in the

neighborhood of 350 volts and that the discharge is interrupted at a voltage but slightly less than the breakdown voltage, as set forth in my first-mentioned application. This operation has been provided for in 60 my second-mentioned application by a ribbed-plate structure. The ribs are difficult to form and are likely to be distorted during formation. Furthermore, the manufacture of plates having such ribs results in 65 a considerable amount of breakage and imperfect plates. It is clear that the gap, which is the subject of this invention, offers many advantages over the rib construction 70 hitherto used in the disk-pile lightning arrester.

When incorporated in a complete lightning arrester of the disk-pile type, including a series gap, difficulty often arises in that the mica spacers have such high resistance 75 that all the line voltage is not concentrated upon the series gap, although it is desirable that the setting of the series gap should limit the line voltage.

To overcome this difficulty, it is merely 80 necessary to provide a leakage path through or past the gap structure so that the line voltage shall always be concentrated upon the series gap. This leakage path is most easily provided for by reducing the resistivity 85 of the mica spacers. This is most readily done by giving the mica spacers a thin coating of india ink.

With the leakage thus provided, the series gap will break down and the arrester will 90 discharge when the line voltage reaches the value for which the series gap is set.

In the accompanying drawings constituting a part hereof and in which like reference characters designate like parts, 95

Fig. 1 is an elevational view showing a gap consisting of two plates of high-resistance material and an insulating spacer therebetween, in accordance with my invention.

Fig. 2 is a vertical cross-sectional view of a lightning arrester made in accordance with my invention, some parts being shown in elevation.

Fig. 3 is an enlarged plan view of one 105 of the plates, showing spacers in position thereon, and

Fig. 4 is a view similar to Fig. 3 but illustrating a slight modification of the invention.

Referring to Fig. 2 of the drawings, which shows a complete lightning arrester, a cylinder 1 of suitable insulating material, such as porcelain, is provided with a petti-
 5 coat 2. A metallic base 3 having a depend-
 ing flange 4, interiorly threaded, as shown
 at 5, is cemented to the lower portion of
 cylinder 1 by means of suitable cement 6.
 Washers 7 are interposed between the base
 10 3 and the cylinder 1. Within the cylind-
 ical opening 8 are assembled a plurality
 of plates or disks 9 of high-resistance ma-
 terial, generally consisting of a suitably
 15 formed mixture of kaolin, carborundum
 and graphite, as described in my copending
 applications above referred to.

Interposed between the adjacent plates 9
 20 are washers or spacers 10 of mica or other
 insulating material, preferably having some
 leakage. The mica washers are of such
 25 diameter that they touch the walls of cyl-
 nder 1, whereas the plates 9 are of slightly
 smaller diameter and are spaced a short
 distance from said walls. The mica spacers
 30 or washers are preferably about 3 to 5
 mils thick, having a coating of india ink.

A metal plate 11 is placed on the upper-
 35 most plate 9 and an insulating ring 12 is
 placed thereupon to support a member 13
 of metal having a depending convexly
 curved portion 14 to provide a series arc gap
 40 between it and the metal plate 11. A spring
 15 is placed on member 13, and a cover is
 secured in position over the assembled struc-
 45 ture. The cover comprises an annular metal
 member 16 provided with exterior screw-
 threads 17 and secured to cylinder 1 by
 means of a suitable cement 18. The cover
 50 also comprises a metal cap 20 having in-
 ternal screw threads to engage the threads
 17. Washers 19 are located between the cap
 55 20 and the top of the cylinder 1 and a termi-
 nal screw 21 secures a conductor 22 to the
 top of the cap.

A screw-threaded member 23 is screwed
 60 into depending flange 4 and has a bracket
 24 firmly secured thereto by means of screw
 65 25. A depending portion 26 on bracket 24
 is provided with a series of openings 27 to
 enable the lightning arrester to be fixed in
 70 position on the cross-arm of a pole or in
 any other suitable position.

Although I have shown the use of annular
 75 mica washers as spacers between adjacent
 plates, it is not necessary that the spacers be
 of such form. For instance, in Fig. 3 I
 have illustrated a series of uniformly spaced
 80 mica disks 28 and in Fig. 4 strips 29, the
 ends of which project beyond the edges of
 85 the plates 9. Said embodiments of my in-
 vention are equally effective in providing
 the desired breakdown voltage, although the
 form illustrated in Fig. 1 has the addi-
 90 tional advantage of preventing accidental
 95 arcing along the outer edges of the plates.

9. By causing the outer edges of the wash-
 ers 10 to project beyond the edges of the
 plates 9, I interpose insulating barriers
 which tend to prevent flashover of the pile.

While I have described several embodi-
 70 ments of my invention, various modifica-
 tions in the structure thereof may be made
 without departing from the principles here-
 in set forth. For instance, any suitable
 75 insulating material may be substituted for
 the mica used and the spacers may be of
 any desired form. A poor insulating mate-
 rial having sufficient leakage may be used
 80 in place of the coated mica. Although the
 plates are spaced apart about 3 mils, it is
 obvious that any other suitable spacing to
 give the desired results may be utilized.
 These and various other changes in the de-
 85 tails of my invention may be made within
 the scope thereof.

Although I have described a preferred
 90 structure as comprising a "plurality of
 plates of relatively high-resistance mate-
 rial", I desire it to be understood that one
 of the plates for each gap or one of the
 95 plates for each of a plurality of gaps but
 less than the whole number may be of rela-
 tively low resistance, such as metal, if de-
 sired. I desire, therefore, that my inven-
 tion shall be understood as comprising these
 100 modifications and such others as may en-
 sure the results hereinbefore specified.

I claim as my invention:

1. A gap structure for lightning arresters
 100 comprising a plurality of plates spaced
 apart and means therebetween to cause the
 gaps between adjacent plates to break down
 at about 350 to 450 volts, at least some of
 105 said plates being of relatively high resist-
 ance material.

2. A gap structure for lightning arresters
 comprising a plurality of plates spaced
 apart and means therebetween to cause the
 gaps between adjacent plates to break down
 110 at about 350 to 450 volts, at least one of
 the plates of each gap being of relatively
 high resistance material.

3. A gap structure for lightning arresters
 comprising a plurality of plates spaced
 apart and spacers therebetween, the average
 115 distance between the plates being approxi-
 mately 3 to 5 mils, at least one of the plates
 of each gap being of relatively high re-
 sistance material.

4. A gap structure for lightning arresters
 comprising a pair of plates and a spacer of
 about 5 mils thickness therebetween, at
 least one of said plates being of relatively
 120 high resistance material.

5. A lightning arrester comprising a plu-
 125 rality of plates of relatively high resistance
 material spaced apart and means therebe-
 tween to cause the gaps between adjacent
 plates to break down at about 350 to 450
 130 volts.

6. A lightning arrester comprising a plurality of plates of relatively high resistance material spaced apart and spacers of insulating material therebetween to cause the 5 gaps between adjacent plates to break down at about 350 to 450 volts.
7. A lightning arrester comprising a plurality of plates of relatively high resistance material and spacers therebetween, the thickness of the spacers being such that the breakdown voltage does not exceed about 450 volts.
8. A lightning arrester comprising a plurality of plates of relatively high resistance 15 material and spacers therebetween, the thickness thereof being 3 to 5 mils.
9. A lightning arrester comprising an enclosing casing, a plurality of plates of relatively high resistance material and insulating washers therebetween, said washers extending beyond the edges of said plates and spacing the same from the walls of said casing, the thickness of said washers being such 20 that the breakdown voltage does not exceed about 450 volts.
10. A lightning arrester comprising a plurality of plates of relatively high resistance material, spacers therebetween, and conducting material on said spacers, the thickness 25 of said spacers being such that the breakdown voltage does not exceed about 450 volts.
11. A lightning arrester comprising a plurality of plates of relatively high resistance material, thin spacers therebetween, and a coating of india ink on said spacers.
12. A lightning arrester comprising a plurality of plates of relatively high resistance material, mica spacers therebetween, the 35 thickness thereof being about 3 to 5 mils, and conducting material on said spacers.
13. A lightning arrester comprising a plurality of plates of relatively high resistance material, mica spacers therebetween, the 40 thickness thereof being 3 to 5 mils, and a coating of india ink on said spacers.
14. A lightning arrester comprising a plurality of plates of relatively high resistance material, spacers therebetween, the thickness 45 thereof being 3 to 5 mils, said spacers extending beyond the edges of said plates and a coating of india ink thereon.
15. A lightning arrester comprising a cylinder of insulating material, a plurality of plates of relatively high resistance material and thin spacers therebetween, said spacers extending beyond the edges of said plates and making contact with the walls of said cylinder.
16. A lightning arrester comprising a series arc gap, a plurality of plates of relatively high resistance material, thin spacers therebetween, and conducting material on
- said spacers, the thinness of said spacers being such as to insure a glow discharge. 65
17. A lightning arrester comprising a series arc gap, a plurality of plates of relatively high resistance material, thin spacers therebetween, providing a plurality of serially connected glow-discharge gaps, and a 70 coating of india ink on said spacers, the resistance and spacing of said plates being such that the breakdown voltage does not materially exceed the voltage at which the discharge is interrupted in said glow-discharge gaps. 75
18. A lightning arrester comprising a series gap, a plurality of plates of relatively high resistance material, mica spacers therebetween, the thickness thereof being 3 to 5 80 mils, and conducting material on said spacers.
19. A lightning arrester comprising a plurality of spaced bodies of relatively high-resistance material and means to cause the 85 gaps between adjacent bodies to break down at approximately the voltage necessary to maintain the discharge.
20. A lightning arrester comprising a plurality of spaced bodies of relatively high-resistance material and means for initiating a discharge between the bodies at a voltage 90 slightly above that necessary to maintain the discharge and then spreading the discharge over the surfaces of the bodies. 95
21. A lightning arrester comprising a plurality of spaced bodies of relatively high-resistance material and means therebetween to cause the gaps between adjacent bodies to break down at approximately the voltage 100 necessary to maintain the discharge.
22. A lightning arrester comprising a plurality of spaced bodies of relatively high-resistance material and means therebetween for initiating a discharge between the bodies 105 at a voltage slightly above that necessary to maintain the discharge and then spreading the discharge over the surfaces of the bodies.
23. A lightning arrester comprising a pair of spaced bodies, at least one of which is of relatively high-resistance material, and means to cause the gap between said bodies to break down at approximately the voltage 110 necessary to maintain the discharge.
24. A lightning arrester comprising a pair 115 of spaced bodies, at least one of which is of relatively high-resistance material, and means therebetween to cause the gap between said bodies to break down at approximately the voltage necessary to maintain the discharge. 120
- In testimony whereof, I have hereunto subscribed my name this 13th day of September 1922.

JOSEPH SLEPIAN.
